UNITED STATES PATENT OFFICE.

JAMES M. RICHARDSON, OF HIGHLAND PARK, MICHIGAN, ASSIGNOR TO TULITE AUTO BULB COMPANY, OF NEW YORK, N. Y., A CORPORATION OF MICHIGAN.

HEADLIGHT.

Application filed August 28, 1919. Serial No. 320,406.

To all whom it may concern:

Be it known that I, JAMES M. RICHARDSON, a citizen of the United States, and residing at Highland Park, in the county of Wayne

5 and State of Michigan, have invented a new and Improved Headlight, of which the following is a specification.

In my United States Patent No. 1,088,094, February 24, 1914, there is disclosed and 10 claimed a headlight for motor vehicles comprising a main filament positioned substantially in the focal center of a reflector together with an auxiliary filament spaced somewhat therefrom and electric circuits 15 whereby the auxiliary filament may be heated independently of the main filament at will: when the main filament is heated, a strong search light suitable for country driving is secured, but when current is passed 20 through the auxiliary filament the light is thrown down upon the roadway to provide a desirable light for street or city use. Due to imperfections incident to the manufacture of the reflector, as well as to other causes, a 25 slight amount of glare, which it is the object of the present invention to eliminate, has been experienced upon heating the auxiliary filament.

This I do by coating, frosting, coloring or 30 otherwise treating the front end portion of the bulb in such manner as to intercept those direct rays from the auxiliary filament which would otherwise strike the reflector and be thrown upwardly into the eyes of an 35 observer standing in the street, while nevertheless limiting such treatment so that the rays incident on the rear portion of the reflecting surface will be reflected forwardly without interference. Thus, when the main 40 filament is heated the rays therefrom are directed forwardly in substantially parallel beams, while when the auxiliary filament is heated its reflected rays sweep forwardly and downwardly over the road to provide a 45 satisfactory illumination without tending to blind an approaching pedestrian or driver. In other words, I screen out those rays which have given rise to glare and retain those primarily effective for illuminating 50 purposes. Although this effect may be attained in various ways, I prefer to render the forward portion of the bulb merely translucent, as distinguished from opaque, 55 since the more direct rays are thus made use of to light up the road at the sides and

close to the lamp; this may be readily done by dipping the front end of the bulb in some suitable mixture or variety of white paint.

The extent of the coating or treatment depends somewhat on the size of the bulb and of the reflector, as well as on the position of the auxiliary filament with reference to the focal center, but to secure the most satisfactory results it should extend back substantially to the vertical plane through the focal center of the reflector when the bulb is properly adjusted therein, or a little further; however, substantial improvements over prior practice may be had even when the treated area terminates forwardly of this plane. The area to be treated is most readily determined by experiment with each type of lamp and bulb.

In the drawings, Fig. 1 is a section showing a preferred embodiment of the invention. Fig. 2 is an enlarged side view of the bulb in position in its socket. Fig. 3 is a view on line 3—3 of Fig. 2. Fig. 4 is a diagram showing the path of rays emanating from the auxiliary filament.

1 indicates an ordinary headlight body carrying the usual lens ring 2, lens 3 and reflector 4 (preferably parabolic) wherein is mounted a lamp socket 5. The latter is electrically grounded to the reflector and is equipped with a bulb 6 having a main filament 7 located substantially in the focal center of the reflector; this bulb also has an auxiliary film 8 preferably positioned above the main filament and substantially in the vertical transverse plane which passes through the focal center. Other bulbs, such as those shown in my patent above referred to wherein the relation of the two filaments is different from that here shown, might be employed, but I prefer the present construction, inasmuch as it provides a proper concentration of light and a sturdy support, particularly for the auxiliary filament. It will be understood that when the switch 10 is thrown to engage the contact 11 current from the battery or other source 12 passes through the main filament 7, and that when the switch is in engagement with the contact 13 current passes through the auxiliary filament 8; and the rays from the former will evidently pass forward from the rear portion of the reflector in substantially parallel relation one to another,

as is usual in such headlights, it being observed, however, that those rays which are intercepted by the treated area 15 of the bulb are diffused downwardly and laterally over the road as heretofore stated.

With reference to the auxiliary filament the action will be best understood from Fig. 4, and as indicated therein, all rays 16 emanating therefrom and striking the reflector 10 rearwardly from the transverse vertical plane 17 through the focal center are reflected downwardly, whereas all rays 18 striking the reflector forwardly of said plane pass upwardly and would theoretically tend to cause 15 glare or blinding when observed by a pedestrian or by the driver of an approaching vehicle. The treated area 15, screening out the rays 18, insures the presence of the downwardly projected primary reflected rays 16 only, but when the treatment is such as to render the glass translucent merely, the rays 18 are diffused downwardly and laterally over the roadway as stated above with reference to the main filament. It is obvious 20 that the screen or treated area need not necessarily be formed directly on the bulb itself, but I prefer the form shown on ac- 25

count of its cheapness and other desirable characteristics.

I claim:—

1. A vehicle head light comprising a reflector having a focal center, a bulb having two filaments, the first of which is located approximately at the focal center and the second a distance from the first but in approximately the same vertical plane, said bulb being frosted over its front surface and back sufficiently far to diffuse all direct rays visible from the front and all reflected rays except enough to make a small 40 central concentrated beam of light.

2. A vehicle head light comprising a reflector having a focal center, a bulb having two filaments, the first of which is located approximately at the focal center and the second a short distance above the first, means whereby said filaments may be separately illuminated, said bulb being frosted over its front surface and back sufficiently far to diffuse all direct rays visible from the front 45 and all reflected rays except enough to make a small central concentrated beam of light 50 whichever filament is illuminated.

JAMES M. RICHARDSON.
